UNITED STATES PATENT OFFICE.

JOSE RUEFF, OF NEW YORK, N. Y.

TELESCOPIC LIFTING JACK.

Application filed April 26, 1923. Serial No. 634,752.

To all whom it may concern:

Be it known that I, JOSE RUEFF, a citizen of the United States, and resident of the borough of Manhattan, city of New York, in the county of New York and State of New York, have invented certain new and useful Improvements in a Telescopic Lifting Jack, of which the following is a specification.

10 This invention relates to telescopic lifting jacks.

The organization of the invention comprises a lifting jack with collapsible telescopic members, that are actuated by a toggle connection, and a worm and wheel. The links of the toggle connection are axially in line when the jack supports its load, and thereby prevents any tendency of the load lowering. The worm and wheel operates 20 the toggle connection and automatically locks it in place.

The object of the invention is the production of a lifting jack which can be easily operated with the members thereof rigidly 25 sustained in position when supporting its load, and which will remain in position without special locking devices; although a lock may be provided therefor.

It is adapted to be applied to a vehicle, especially an automobile without changing the construction of the latter, and is adapted 30 to lift and lower the vehicle with its wheels from the ground, and to lift and lower various other objects.

35 In the accompanying drawings Fig. 1 represents a front view of an exemplification of the telescopic lifting jack in operative position; Fig. 2 shows a section of Fig. 1 on the line 2, 2; Fig. 3 represents a view 40 similar to Fig. 1, with the jack in its collapsed position; Fig. 4 indicates a section of Fig. 2 on the line 4, 4; Fig. 5 represents a front view of a modification of the telescopic lifting jack connected to the axle casing of 45 a vehicle; Fig. 6 shows a section of Fig. 5 on the line 6, 6; Fig. 7 indicates a side elevation of the lifting jack when collapsed and locked to its axle casing; Fig. 8 shows 50 a bottom plan view of Fig. 7 and Fig. 9 represents a view similar to Fig. 5 with a further modification.

Referring to Figs. 1 to 4 the lifting jack comprises the bottom guide barrel 20, that has formed therewith the longitudinal guide 55 slot 21 and the lug 23.

A movable sleeve 24 is guided in the bar-

rel 20 and has extending therefrom the guide pin 25 and the journal pin 27. A housing 28 with the journal bearings 29 extends from and is formed with the sleeve 60 24. A worm wheel 30 is journaled on the pin 27 and is maintained in operative position by means of the washer 31. A worm shaft 35 with the worm 36 is journaled in the bearings 29, and has formed therewith 65 the square operating end 37. The latter is adapted to have a wrench applied thereto. The worm 36 meshes with the worm wheel 30. A pair of diametrically oppositely positioned journal pins 40 and 41 extend from 70 the worm wheel 30. A journal pin 42 extends from the lug 23. A toggle link 45 connects the journal pins 40 and 42.

A movable plunger 46 is guided in the sleeve 24 and has mounted thereon the head 75 47 with the concaved upper face 48. A lug 49 is formed with the head 47 and has extending therefrom the journal pin 50. A longitudinal guide groove 51 is formed in the plunger 46 and engages the guide pin 80 25 of the sleeve 24. A toggle link 53 connects the pins 41 and 50. The barrel 20, the sleeve 24 and the plunger 46 constitute the collapsible telescopic members of the lifting jack and the toggle links 45 and 53 85 85 with the worm wheel 30, constitute a toggle connection.

To operate the telescopic lifting jack it will be noted that Figs. 1 and 2 show it in its extended position and Fig. 3 shows the jack 90 in its collapsed position. The object to be raised or lowered bears on the face 48 of the head 47. To lower the head 47 from the position shown in Figs. 1 and 2, the operator applies a wrench to the square end 37 of 95 the worm shaft 35 and turns the latter, whereby the worm wheel 30 is turned. By this means the toggle link 53 is lowered and swung into position shown in Fig. 3 and the toggle link 45 is swung to the position shown in said figure. The toggle link 53 pulls down the head 47 with its plunger 46 and at the same time the sleeve 24 is lowered, all with the coaction of the toggle link 45. Thereby both the plunger 46 and the sleeve 24 enter the barrel 20, the plunger 46 moving faster than the sleeve 24. The engagement of the worm 36 with the worm wheel 30, at all times locks the movable elements in position, and avoids any danger 100 whatever of the head 47 with its load being inadvertently lowered by accident. It is to

be noted that when the head 47 supports its load, the toggle links 45 and 53 are vertically in line, which prevents any tendency for the load to lower.

In Figs. 5, 6, 7 and 8 the same general construction of a telescopic lifting jack is indicated. It comprises in this instance the bottom post 60 having the longitudinal guide groove 61, and the foot 62 having extending therefrom the journal pin 63. A movable sleeve 65 encircles the post 60 and has formed therewith at its lower end the housing 66 with the journal bearings 67. A guide pin 68 extends from the sleeve 65 and engages the guide groove 61. A journal pin 70 extends from the sleeve 65. A worm wheel 71 with the opening 72 in its web is journaled on the pin 70 and has extending therefrom the journal pins 73 and 74. A worm shaft 75 is journaled in the journal bearings 67 and has formed therewith the worm 76 and the square end 77. An upper sleeve 80 with the head 81, the longitudinal slot 82, and the flange 82^a having an opening that can register with the opening 72 of the worm wheel 71 encircles the sleeve 65. The hasp of a lock 82^b can engage the said opening 72 and the opening in the flange 82^a. The sleeve 80 has formed therewith a pair of side journal brackets 83 that are hinged to the axle casing 84, by means of the pins 85. A U-shaped bracket 86 with the boss 87 extends from the sleeve 80, and supports the journal pin 88. A toggle link 89 connects the journal pins 74 and 88 and a toggle link 90 connects the journal pins 63 and 73. A latch 94 is pinned to the axle sleeve 84, by means of the pin 95 and can lock with a hook 96 extending from the sleeve 80, to lock the telescopic lifting jack in operative position. A spring 97 has one end fastened to the axle sleeve 84 and its other end bears against the latch 94. A plate spring 99 extends from the axle casing 84 to bear against the sleeve 80 to prevent jar when it is swung up under said axle casing. A second latch 100 is hinged on a pin 101 extending

from the axle casing 84, and is adapted to engage a hook 102 extending from the foot 62, when the telescopic lifting jack is not in use and swung up and locked adjacent to the axle sleeve 84. A spring 103 has one end thereof fastened to the axle sleeve 84 and its other end bears against the latch 100. A wheel is indicated at 105 for the axle sleeve 84. In Fig. 9, the telescopic lifting jack is represented with its upper sleeve 80^a, having a flange 108 that is fastened to the axle sleeve 84, by means of the screws 109. The sleeve 80^a has extending therefrom the U-shaped bracket 86 with the boss 87. In this modification the bottom post 60, the foot 62, the journal pin 63, the housing 66, bearings 67, journal pin 70, journal pins 73, 74, worm shaft 75, worm 76 and toggle links 89 and 90 are constructed as already explained. The worm wheel 71^a in this modification is indicated without the opening 72, although it may be provided with the same.

Various modifications may be made in the invention and the present exemplification is to be taken as illustrative and not limitative thereof.

Having described my invention what I desire to secure by Letters Patent and claim is:

In a lifting jack the combination of a bottom guide barrel, a slideable sleeve guided in the barrel, a slideable plunger guided in the sleeve, a worm wheel adapted to turn journaled to said sleeve, a worm adapted to turn journaled to the sleeve and meshing with said worm wheel, a toggle link with one end pinned to said worm wheel and its other end connected to said barrel and a second toggle link with one end pinned to said worm wheel and its other end connected to said plunger.

Signed at the borough of Manhattan, city of New York, in the county of New York and State of New York, this 20th day of April A. D. 1923.

JOSE RUEFF.
